TUCK COMB

James Redmond McEleney, Leominster, Mass.

Application January 2, 1948, Serial No. 317

8 Claims. (Cl. 132—31)

1

This invention relates to tuck combs, coiffure combs, and devices of like nature.

The principal object of the invention resides in the provision of a device of the class described having a completely novel and greatly improved means for securing the same to the head of the wearer, said means being of a nature not only holding the hair positively to the comb but also acting to insert the hair in between the teeth of the comb in the application of the comb to the hair.

A further object of the invention resides in the provision of a toothed article in the nature of a comb in which the teeth are each formed with a slot extending longitudinally of the teeth centrally thereof in combination with a slider or tongue which is held in the combined slot in a slidable manner and which is provided with an inclined nose or forward end portion which lifts the hair and wedges it into the spaces between the teeth of the comb.

A further object of the invention resides in the provision of a toothed device in the nature of a comb having teeth, which teeth are slotted, the slots in the teeth together forming a guideway for the reception of a slider or tongue which extends at one edge to a line connecting the points of the teeth and having an upwardly inclined portion acting as a cam to pick up the hair and wedge it in between the spaces of the teeth, the comb being placed with the points of the teeth against the scalp and the slider or tongue running the guideway formed by the teeth adjacent the scalp.

Other objects and advantages of the invention will appear hereinafter.

Reference is to be had to the accompanying drawings, in which:

Fig. 1 is a view in front elevation showing the invention with the slider or tongue removed;

Fig. 2 is a top plan view of the same;

Fig. 3 is a section on line 3—3 of Fig. 1;

Fig. 4 is a section on line 4—4 of Fig. 1;

Fig. 5 is a view similar to Fig. 1 but showing the slider or comb in position;

Fig. 6 is a top plan view of a modification;

Fig. 7 is a view in front elevation of the modification of Fig. 6;

Fig. 8 is a section on line 8—8 of Fig. 5 but showing only a section of the slider or tongue;

Fig. 9 is a view in front elevation of a slider or tongue for the modification shown in Figs. 6 and 7; and

Fig. 10 is a section on line 10—10 of Fig. 7.

This invention comprises two separate parts which, however, are assembled as will be later described so as to form a single unitary article in which the two parts are substantially permanently connected.

The main part of the device comprises a body

generally indicated at 10 in Figs. 1, 2, and 5, this body, as will be seen in Fig. 2, being wider than an ordinary comb and as seen in Figs. 3 and 5 it may be made on a curve in its preferred form, although it may also be made straight.

The part 10 is provided with a series of teeth 12 and end teeth 14 and 15, each one of which, except for the enlarged end tooth 14, has a cross sectional shape as shown in Fig. 3. This shape 10 provides a pair of spaced legs 16 forming an enlarged central slot or opening at 18 and a narrow necked down central slot or opening 20 at the points 22 of the teeth. The slots or openings 20 and 18 in the series of teeth form an undercut 15 guideway for the reception of a slider or tongue generally indicated at 24. This tongue has a cross sectional shape as shown in Fig. 8 including an enlarged portion which will fit in the enlarged slots or openings 18 and a smaller portion 26 20 which will be received in the smaller slots or openings 20. One of the important characteristics of this slider or tongue is that when assembled in the guideway formed by the openings in the teeth its lower edge 28 falls along a line joining 25 the points of the teeth of the comb as is plainly shown in Fig. 5.

The slider or tongue 24 is also provided at each side with a continuous groove 30 and this receives inwardly directed projections 32 in the 30 end tooth 14. The grooves 30 stop short of the left hand end of the slider or tongue as shown in Fig. 5, and thus it will be seen that the same cannot be withdrawn from assembly with the comb 10 once it has been snapped into position, 35 because the end of the groove 30 forms a stop which will abut against the projections 32.

One of the most important characteristics of the slider or tongue 24 is that at its left hand end, as seen in Fig. 5, it is provided with an inclined 40 end edge 34, which is as great as or greater in extent than the space between the back 10 and the slider itself. In other words, the effective portion of the inclination, which is the width of the slider, is great enough to insure a solid packing of hair in the spaces indicated below the teeth 12, and to this end is approximately equal to the space between the slider and back. The slider or tongue may be originally straight, receiving its curved form by reason of being bent 45 or curved due to the bent or curved formation of the comb 10. In other words, the slider or tongue 24 is resilient to some extent, and both parts of the device are most practicably made of molded plastic material which is inherently resilient.

In the operation of the device, the slider or tongue 24 is withdrawn as far as possible to the right so that most of the teeth 12 are open. Then the device is thrust into the hair, the curved line 50 at 28 conforming substantially to the scalp, and

the slider is thrust through the teeth to the Fig. 5 position. Since the edge 28 is substantially in contact with the scalp it will be obvious that the inclined edge portion 34 will lift up the hair and thrust it into the spaces between the teeth, wedging it in position so that the device is practically impossible to withdraw from a head of reasonably thick hair without first withdrawing the slider or tongue 24.

As shown in Figs. 6 and 7, the same principle may be applied to a more usual type of comb having teeth such as those at 36. In this case, the teeth 36 extend laterally from a back portion 38 and the teeth are slotted as above described, as clearly shown at 40, for the reception of a similar slider or tongue 42 provided with an upstanding rib 44 which will lie along a line joining the terminations of the teeth as at 46 in Fig. 6. In this modification, the comb is used in the same manner and it will be seen that the teeth 36 do not enter the hair at all except to be thrust into the hair in the manner of a tuck comb. The hair is wedged by the slider 42 to lie against the portions of back 38 between teeth 36, and is so held by the slider.

It is pointed out that the device shown in Fig. 1 is held perpendicularly to the scalp and the thrusting action of the slider or tongue in picking up and wedging the hair to the teeth 12 acts only perpendicularly to the scalp to maintain parallel arrangement of and even distribution of the hair. Also, the slider or tongue 24 originally being straight, is actually frictionally locked in engagement in the Fig. 5 position due to the curve impressed thereon by the tooth arrangement forming a curved guideway.

Having thus described my invention and the advantages thereof, I do not wish to be limited to the details herein disclosed otherwise than as set forth in the claims, but what I claim is:

1. A device of the class described comprising a back, a series of teeth connected to the back and each having a central slot extending inwardly from the points of the teeth, the slots each being enlarged inwardly from the teeth points and alined, and a slider spaced from the back and received in the slots and adapted to be moved centrally through the teeth to wedge hair into the spaces between the teeth, said slider having its forward end inclined relative to the teeth, from one side edge to the other side edge, so that all hair abutting the forward end of the slider is wedged toward the back.

2. A device of the class described comprising a back, a series of teeth connected to the back, each tooth having a central slot extending inwardly from the points of the teeth, the slots each being enlarged inwardly from the teeth points and alined, a slider spaced from the back and received in the slots and adapted to be moved centrally through the teeth to wedge hair into the spaces between the teeth, said slider having its forward end inclined relative to the teeth, the effective width of the slider being approximately equal to the space between the slider and back.

3. A device of the class described comprising a back, a series of spaced teeth thereon, said teeth being centrally slotted inwardly from the points thereof, and a slider spaced from the back and arranged to slide in the slots, said slider having a hair picking up inclined forward end, the back and the slider being originally non-parallel and the latter being resilient to assume the shape of the former.

4. A device of the class described comprising a back, a series of spaced teeth thereon, said teeth being centrally slotted inwardly from the points thereof, and a slider spaced from the back and arranged to slide in the slots and having an edge coinciding with the line of the tooth points, said slider having a hair picking up inclined forward end, and means preventing total withdrawal of the slider from the device, the back and the slider being originally non-parallel and the latter being resilient to assume the shape of the former.

5. A device of the class described comprising a back, a series of spaced teeth thereon, said teeth being centrally slotted inwardly from the points thereof, and a slider spaced from the back and arranged to slide in the slots and having an edge coinciding with the line of the tooth points, said slider having a hair picking up inclined forward end, and means preventing total withdrawal of the slider from the device, said means comprising an inwardly directed projection on the last tooth of the device, the slider being longitudinally recessed to receive the projection.

6. A device of the class described comprising a back, a series of slotted spaced teeth thereon, a slider spaced from the back and in the slots and guided thereby, and an inclination at one end of the slider to pick up hair and force the same into the spaces between the teeth, said inclination extending from one side of the slider to the other and approximating in effective width the distance from the back to the slider, the slots being enlarged inwardly of the points of the teeth and the slider being enlarged correspondingly so that the latter is held to the teeth and is guided in the slots.

7. In a device of the class described comprising a back, a series of slotted spaced teeth thereon, a slider spaced from the back and in the slots and guided thereby, and an inclination at one end of the slider to pick up hair and force the same into the spaces between the teeth, said inclination extending from one side of the slider to the other and approximating in effective width the distance from the back to the slider, the slider having an edge coinciding with a line connecting the points of the teeth.

8. A device of the class described comprising a back, a series of slotted teeth thereon, a slider spaced from the back and in the slots and guided thereby, an inclination at one end of the slider to pick up hair and force the same into the spaces between the teeth, said inclination extending from one side of the slider to the other and approximating in effective width the distance from the back to the slider, the teeth being located on the arc of a curve and the slider being substantially straight and resilient to be forced into conformance with said curve.

JAMES REDMOND McLEENEY.
